PRODUCE WASHING MACHINE

Leland H. Platt, Leland H. Platt, Jr., and
John D. Platt, Los Angeles, Calif.

Application May 13, 1946, Serial No. 669,305

2 Claims. (Cl. 198—108)

1

This invention has to do with improvements in equipment for washing produce, for example carrots and other vegetables, particularly of the type in which the produce is carried on or advanced along a flexible belt contained in a housing or tank with the produce being washed by water sprays directed downwardly from above the belt. More specifically, the invention relates to improvements in this type of washer employing a horizontally extending belt anchored at one or more locations against bodily advancement, and actuated by a mechanism operating to effect up and down wave-like deflections of the belt, occurring at such timed or sequential relation as to advance the produce through the washing zone. Structurally, the invention contemplates positioning the belt with its edges in close proximity to side walls of the housing, or an overlying hood structure, and producing wave-like deflections of the belt by a mechanism contained within the housing below the belt and acting to impart thereto alternating up and down deflections, as and for the purpose forward.

One of our primary objects is to provide important improvements assuring against the interruption, congestion or fouling of the produce advancement at the edges of the belt, by reason of its engagement with the side walls of the housing, as has been found to occur where the housing sides above the belt surface, have openings or irregularities capable of receiving or arresting the produce. As illustrative, difficulties of this character have been encountered in carrot washers by reason of the tendency of the carrot tops or ferns to enter and become retained within any consequential openings in the housing walls. According to the invention, such walls are made to present closed or non-apertured surfaces assuring free advancement of any produce engaging them at the edges of the belt.

Another feature and object of the invention is an improved belt deflecting mechanism comprising successive pairs of members or rods extending transversely below the belt, and carried for rotation of the individual pairs into engagement with the under surface of the belt, by plate-like supports or discs mounted for rotation inside and adjacent the housing walls. By properly positioning and timing the rotation of the individual units or rod pairs, the belt is deflected in wave-like progression effecting uniform advancement of the produce, all in a manner permitting confinement of the deflecting mechanism below the belt and maintaining by virtue of the proximity of the carrier discs to the housing walls, the desired wall continuity and freedom from obstructions, referred to above.

A further important object is the provision of means for so controlling or limiting the belt deflection in a downward direction, while permitting its free upward deflection, as to avoid buckling or

2

doubling tendencies which might otherwise interfere with proper progression of the belt deflection and uniform advancement of the produce. In this connection, the invention contemplates, preferably by incorporation in the belt itself, novel means whereby portions of the belt between and extending rearwardly from anchor locations, are maintained against downward deflections such as might otherwise result in tendencies for the belt to buckle and consequently retain the produce against regular advancement.

All the various features and objects of the invention will be understood to better advantage from the following detailed description of the typical and illustrative embodiment shown by the accompanying drawings, in which:

Fig. 1 is a longitudinal sectional view of the washer;

Fig. 2 is an enlarged cross-section on line 2—2 of Fig. 1;

Fig. 3 is a fragmentary side view taken on line 3—3 of Fig. 2 between tank and hood structure;

Fig. 4 is a fragmentary view of the woven wire belt showing the affixed stop plates;

Fig. 5 is a fragmentary enlarged view illustrating one of the belt anchor locations and deflecting rods; and

Fig. 6 is an enlarged fragmentary section as viewed on lines 6—6 of Figs. 2 and 5.

The washing machine assembly is shown to comprise a housing structure, generally indicated at 10, the specific shape, size and details of which may be varied to suit the purposes of particular designs. Typically, the housing structure is shown to comprise a lower or tank section 11 and an overlying cover or hood section 12, the vertical side walls 13 of which extend parallel with and in spaced relation at 14 to the sides of the tank 11, as shown in Fig. 2. The tank may be supported on a suitable frame structure 15, and is shown to have an inclined bottom 16 from directly above which an outlet 17 extends through one side of the tank. Water entering the diagrammatically illustrated pump 18 from the outlet, is discharged upwardly through pipe 19 into header 20 from which the water passes into pipes 21 to be sprayed downwardly over the produce carried on the belt as later described.

The belt, generally indicated at 22, extends in a horizontal course within the housing, may be made of a flexible woven wire belt 23, typically in the form shown in Fig. 4 to comprise flattened spiral wire loops 24 turned about the transverse wires 25 to give the material longitudinal flexibility. The ends of the belt are suitably anchored at 26 and 27 as by attachment to rods 28 which may extend through the side walls of the hood 12 to support and secure the hood in position. The specific forms of the attachment at 26 and 27 may correspond with the belt anchors later

described with reference to Fig. 5, by welding the belt ends to sleeves 29 carried on the rods.

The belt waving mechanism generally indicated at 30 comprises a horizontal series of units 31 each consisting of a pair of plate metal discs 32 substantially in surface engagement with the side walls 13 of the hood, and carrying a pair of diametrically opposed rods 33 extending transversely beneath the belt 23. Discs 32 are carried on trunnions 34 extending through open bottom recesses 35 in the lower edges of walls 13, and journaled in bearings 36 mounted on angle brackets 37 attached to the tank 11. Each of the trunnions 34 carries a sprocket 38 having attachments at 39 with the disc 32, thus in effect integrating and re-enforcing the disc, sprocket and trunnion assembly. As shown at the left in Fig. 2, one of the trunnions 34a may be extended at 40 through the side of the tank to carry a sprocket 41 driven by chain 42 from a suitable power source. One or more of the trunnions may similarly be extended through both sides of the tank to carry drive sprockets.

Referring to Fig. 3, the sprockets 38 in each series along the outsides of the hood 12, are interconnected for rotation together by an endless chain 44 passing beneath and engaging the idler sprockets 45. Referring to Fig. 6, sprockets 45 may be supported for idling rotation about shafts 46 terminally carried within brackets 47 attached to the tank wall, and extending transversely beneath the belt 23. Thus the drive transmitted from sprocket 41 and shaft 34a to one of the sprockets 38, is transmitted by chain 44 to all the sprockets 38, causing disc 32 to rotate at the same speed in the direction of the arrows in Fig. 1.

The belt 23 is anchored at uniformly spaced intervals to the shafts 46, as by welding the belt at 48, see Fig. 5, to rotatable sleeves 49 carried by the shafts. Between its points of attachments to the shafts 46, the belt has sufficient looseness or slack for the production of progressive wave-like inflections by the mechanisms 30, as will now appear.

Trunnions 34 may be positioned at an elevation in substantial alinement with shafts 46, so that upon rotation of the discs 32, the rods 33 alternately engage and disengage the undersurface of the belt to deflect it in the progressively varying trough formations illustrated in Fig. 1. Assuming the produce to enter the washer upon the inclined surface 50 and to be deposited upon the inlet end of the belt. With the rods 33 positioned in horizontally opposed relation, the belt 23 assumes between the rods trough formations substantially as shown. Then upon rotation of the rods through the progressive stages and positions illustrated, the right-hand end portions of the belt sections between their anchor points, become progressively elevated in a sequence and relationship causing the belt to assume advancing wave-like deflections which displace the produce at a steady and regular rate to the discharge end of the belt. During progression of the produce over the belt, it is showered and washed with water from the spray pipes 21, the water collecting in the tank and being returned through pipe 19 to the spray header, as previously explained.

It will be observed that the side walls 13 of the hood, and the discs 32 arranged substantially in surface engagement with the hood, present above the belt 23 a continuous or non-apertured wall, free from any irregularities, openings or other obstructions which might retain or arrest the move-

ment of produce carried at the edges of the belt 23 and engaging the hood wall. This feature effectively eliminates the difficulties heretofore experienced in preventing the produce from lodging or becoming lodged or entangled beyond the edges of the belt.

Referring again to Fig. 1, it has been found that when under load, a belt having free downward flexibility between the anchor locations, or throughout an extent approaching each anchorage, may tend to sag and become buckled or doubled upon itself by the advancing rod 33, to a degree resulting in the formation of a pocket from which the produce will not become displaced, at least at a regular rate of advancement. Accordingly, provision is made for limiting downward flexibility of at least those portions of the belt which otherwise would tend to assume the stated doubled and pocketed condition. Referring to Fig. 4, the belt 23 is shown to carry throughout that extent of the belt to be limited against downward deflection, a series of relatively small flat plates 54, each welded at 55 to one of the spiral loops 24, and extending in overlapping relation with the adjacent loops. The successive loops 24 are free to turn about the transverse wires 23 in one direction, thus giving the belt free upward flexibility, but successive loops throughout the course of the belt to which the stop plates 54 are applied, are arrested against downward flexure beyond positions of substantially straight alinement longitudinally of the belt. Thus as the rods 33 advance along the belt, and say to the position of rod 33a in Fig. 1, the belt span rearwardly from the anchor shaft 46a will assume a non-sagging condition, assuring complete passage of the produce into the trough beyond.

We claim:

1. Produce washing equipment comprising a flexible belt, a housing including vertical walls extending along and in close proximity to the sides of the belt, a series of opposed pairs of vertical discs rotatable adjacent the insides of said walls, a pair of rods carried by each opposed pair of discs and extending transversely beneath the belt, said rods operating alternately to engage and elevate the undersurface of the belt, and means for driving said disc pairs to effect progressive wave-like deflections of the belt to advance the produce thereon.

2. Produce washing equipment comprising a horizontally extending woven wire flexible belt, means anchoring said belt at fixed longitudinally spaced locations, means engageable with the undersurface of the belt to produce up and down progressive wave-like deflections to advance the produce thereon, said belt having free upward flexibility between said locations, and metallic stop plates carried by the belt and engageable therewith to limit downward flexure of portions thereof extending rearwardly from said locations.
